UNITED STATES PATENT OFFICE.

ABRAM SCHENCK BERGEN, OF HUNTINGTON, NEW YORK.

CARBURETER.

1,258,389.

Specification of Letters Patent.

Patented Mar. 5, 1918.

Application filed November 18, 1914. Serial No. 872,708.

To all whom it may concern:

Be it known that I, ABRAM SCHENCK BERGEN, a citizen of the United States, and a resident of Huntington, in the county of 5 Suffolk and State of New York, have invented new and useful Improvements in Carbureters, of which the following is a specification.

My invention relates to improvements in carbureters of the automatic type, and the objects of my invention are to provide a simple and efficient carbureter which will supply throughout its entire range the proper proportions of finely pulverized fuel 10 and air thoroughly mixed, to provide ready means for varying the ratio between the quantity of fuel and the quantity of air, and to provide means for automatically varying the effective area of the air and fuel intake 15 ports to correspond with the demand made upon the carbureter for mixture.

The other objects and essential features of my invention are pointed out in the following specification and in the appended claims.

I attain these objects by the mechanism illustrated in the accompanying drawings which disclose the preferred form of my invention, in which—

Figure 1 is a side elevation of a carbureter 30 embodying the present invention.

Fig. 2 is a vertical longitudinal sectional view of the carbureter on a line of section that includes the float chamber.

Fig. 3 is a view partly in section on the 35 line *a—a* of Fig. 2.

Fig. 4 is a plan view of a portion of my apparatus partially in section on the line *b—b* of Fig. 2.

Fig. 5 is a view of the base of the mixing 40 chamber partly broken away.

Fig. 6 is a plan view of the base of the mixing chamber showing the air nozzle and the spray nozzle.

Fig. 7 is a section of the mixing chamber 45 on the line *c—c* of Fig. 2.

Fig. 8 is a sectional view on the line *d—d* of Fig. 7.

My carbureter is provided with a float feed chamber 1, to which liquid fuel is admitted from any suitable source of supply 50 through a pipe not shown, connected with

the bushing 2 by a suitable connection not shown. The bushing 2 is mounted in the member 3 which is tapped and screw-threaded to receive and retain it in position. 55 The base of the float chamber is tapped and screw-threaded to receive the reduced screw-threaded upper end of the member 3, which is provided with a shoulder 4, which is seated against the lower face of the float chamber 1 to insure a tight connection and prevent leakage. The member 3 is provided with a central passage 5 and lateral passages 6, through which the liquid fuel is admitted to the chamber. The upper portion of the 60 passage 5 is enlarged and a conical valve seat 7 is formed below the lateral passages 6. The float chamber 1 is provided with a cover 8, which is removably secured in position by the studs 9. This cover is provided with a central guide opening 10, in which is mounted a stem 11, which is tapped and screw-threaded to receive the upper screw-threaded stem of the needle valve 12. Levers 13 are pivoted at 14 to lugs 15 on the 65 cover 8. Balls 16 on the inner ends of these levers fit in sockets 19 on the stem 11, and the outer ends of the levers 13 are provided with balls 17 of sufficient weight to normally lift the needle valve 12 from its seat 7 when liquid fuel will flow from the source of supply into the chamber 1, until the float 70 18 is lifted, raising the outer ends of the levers 13 until the needle valve 12 is forced against its seat 7 and the flow of fuel is cut off; by these means a constant level of fuel 75 is maintained in the chamber 1. Leading from the float feed chamber 1 is a passage 22, which communicates with the chamber 23 in the base 24. The base 24 is tapped and screw-threaded at 25 to receive the bushing 26, which is provided with a shoulder 27 adapted to seat against the lower face of the base 24. In order to prevent leakage, I prefer to solder this bushing to the base 27 when in position. The bushing 26 is tapped and screw-threaded to receive the spray nozzle 28. In order to prevent leakage, I provide a stuffing-box 29, containing packing 29a, which has a screw-threaded engagement with 100 the upper projecting end of the bushing 26. In order to prevent leakage around the

lower portion of the jet 28, I provide a stuffing box 30 containing packing 30^a, which has a screw-threaded connection with the lower end of the bushing 26. The spray nozzle 28 is adjustable as to height through the bushing 26, the lower end of the spray nozzle 28 being provided with a hole 31, through which a pin may be introduced for the purpose of rotating it. The nozzle 28 is provided with openings 32 and 33 communicating with the passage 22, and also with the passage 34, so as to permit liquid fuel to flow from the float feed chamber 1 into the chamber 34. A fixed air nozzle 35 is secured to the base 24 by screws 35^a and surrounds the spray nozzle 28. Air openings 36 in the base communicate with the air nozzle 35. The air nozzle 35 is also provided with openings 37, more clearly shown in Fig. 5. Mounted on the base 24 is a ring piston 38, which is loosely secured in place by the ring 39, which in turn is secured to the base 24 by the screws 40, as shown in Fig. 8, and the purpose of which will be hereafter explained. The cylindrical main mixing chamber 41 is secured to the base 24 by the divided ring 42, which seats in the annular groove 43 and the collar 44, which is secured to the base 24 by the bolts 45 and nuts 46, as shown in Fig. 1, thus rendering it possible to rotate the float chamber 1 to any desired position. This cylinder 41 is provided with air ports 47 and 48 in two series, one arranged above the other. The upper portion of the cylinder is contracted into a neck 49, in which is mounted the usual throttle valve 50. The upper end of the neck is provided with a flange 51, which is adapted to be secured to the flange of the manifold on an explosive engine. Mounted in the main mixing chamber 41 is a piston valve 52, provided at its lower end with an annular chamber 53, which is adapted to receive the ring piston 38, the ring piston 38 being loosely secured to the base so as to accurately register therewith. The ring piston 38 is provided with a passage 54^a of very limited size, so that when the suction of the engine tends to raise the piston valve 52 its movement is retarded by the partial vacuum created in the chamber 53, and the rapidity with which this piston may be raised or lowered is determined by the size of the passage 54^a, the whole operating after the manner of a dash-pot, its object being to prevent undue fluttering of the piston. The walls of the piston valve 52 are provided with two series of air ports 54 and 55, which to a greater or lesser extent register respectively with the air ports 47 and 48 in the walls of the cylinder 41, when the piston valve 52 is elevated by the suction of the engine. 56 are air ports forming passages through the base of the piston valve, the purpose of

which will be hereafter explained. Mounted 65 within the piston and secured thereto by screws 57^a is the tubular member 57, which surrounds the nozzle 35, and which is provided at its upper closed end with a socket 58, in which is mounted the ball 59 on the 70 upper end of the needle valve 60, the ball being loosely secured in position by the cap 61. The needle valve 60 extends down into the spray nozzle 28 and is provided at its lower end with a spider 62, which centers it 75 in the nozzle 28. As shown, the needle valve 60 is tapered for the purpose which will be hereafter explained. The upper portion of the tubular member 57 is provided with a plurality of small perforations 63 80 forming outlet openings from the tubular member 57, or primary mixing chamber to the chamber 41.

The operation of my invention is as follows:

Gasoline is mainly fed in the float feed chamber 1 at a constant level and through the passages 22 and 33 and the ports 32 and 33 is also maintained at a constant level in the passage 34 of the spray nozzle 28. When 90 but a small quantity of mixture is demanded, air is admitted through the air ports 36 into the air nozzle 35, the major portion of the air so admitted passing upward through the air nozzle past the spray nozzle 28, where it 95 meets and pulverizes the film of gasoline or other liquid fuel drawn from the spray nozzle 28 around the needle valve 60 into the carbureting chamber 57, where it meets a small quantity of air which has passed 100 through the ports 37 and through the annular space between the air nozzle 35 and the member 57. From this point it passes upward through the member 57 and out through the small perforations 63, which aid 105 materially in pulverizing the liquid fuel, into the main mixing chamber of the carbureter, where it also meets and mingles with a small quantity of air which has passed 110 through the perforations 37 and through the ports 56 into the main mixing chamber, from which point it is carried past the throttle valve and through the manifold to the engine. The amount of air and mixture which is thus admitted is comparatively small, and I prefer to so construct the ports that the amount so admitted will be only sufficient to turn the engine over idle at a comparatively slow speed. When the demand for a larger quantity of mixture is 115 made the piston valve 52 is elevated by the suction of the engine until the air ports 54 and 55 in the piston valve 52 register to a greater or lesser extent with the air ports 47 and 48 in the cylinder 41, thereby opening 120 additional air ports which admit an increased quantity of air corresponding to the demand made for mixture. At the same

time the needle valve 60, which is properly tapered to accomplish this purpose, increases the area of fuel port and an increased quantity of fuel is supplied by the apparatus, the needle valve being purposely so tapered and adjusted with reference to the nozzle 28, that at all times and under all conditions a mixture will be supplied containing the proper quantities of both fuel and air to produce the maximum results. When but a small quantity of mixture is demanded and the engine to which the carbureter is connected is operating under a low compression, a comparatively rich mixture is demanded, and as the demand for mixture is increased and the compression in the engine to which the carbureter is connected is also increased, a leaner mixture is supplied, the richness of the mixture under these varying conditions being determined by the taper of the needle valve. The ratio of the fuel to the air supplied may be varied throughout the entire range of my carbureter by raising or lowering the nozzle 28 with reference to the needle valve 60, the ports 32 and 33 being so arranged that the nozzle may be raised or lowered without closing these ports.

I have found it desirable to cause a small portion of the air which passes through the ports 36 and through the ports 37 of the air nozzle and upward between the air nozzle and the member 57, so as to carry with it any liquid fuel which may be condensed on the walls of the member 57 and which would otherwise tend to collect in the base of the carbureter. The purpose of the ports 56 is to prevent any accumulation of liquid fuel at the base of the piston valve 52 caused by condensation in the main mixing chamber. As shown in the drawings, the ports 48 and the ports 47 are each seven in number, whereas the ports 54 and the ports 55 are each four in number, with the result that no matter to what position the piston valve 52 may be rotated with reference to the cylinder 41 the area of the air ports uncovered by lifting this piston to a certain height always remains constant. I have so arranged the ports 63 that they are slightly above the ports 55 in the piston in order to insure a complete and thorough mingling of the air entering through the ports in the piston valve and the mixture entering the main mixing chamber through the ports 63.

One criterion that may be applied in determining the number, form, and arrangement of the ports in the respective members to maintain the area of the air intake openings uncovered by the piston, may be stated as follows:

Divide the circumference between the two members into as many equal parts as the product of the number of ports in the piston

multiplied by the number of ports in the casing, the ports in each member being equidistant from each other and of equal width and form, and the partition walls in one member being of a width at least equal to one of the equal divisions of the said circumference.

The number of ports in one member must be greater than the number of ports in the other member, and when the number of ports in one member is a multiple of the number of ports in the other member, the width of the walls between the ports in the member having the lesser number of ports must be at least equal to that portion of the circumference which is equal to the divisions obtained by dividing the circumference into as many equal parts as the number of ports in the member having the largest number of ports.

I have found that appreciably better results are obtained by providing a carbureting chamber to which practically all of the air and all of the liquid fuel is admitted when but a small quantity of mixture is demanded and then discharging this mixture into the main mixing chamber through a considerable number of small perforations, this method insuring better pulverization of the fuel and a more complete mixture of the air and pulverized fuel. This method also produces a more perfect mixture of the over-rich mixture which is discharged from the carbureting chamber into the main mixing chamber when air is admitted to the main mixing chamber through the ports in the walls thereof. And I have also found that the quality of the mixture is improved by forming the ports in the side walls of the main mixing chamber and in the valve controlling said ports in two series, one above the other, 105

Having described my invention, what I claim as new and desire to secure by Letters Patent is:

1. A carbureter comprising in combination a mixing chamber, ports for admitting air thereto, a piston valve adapted to normally close said ports and to be lifted by suction, an annular chamber in the base of said piston valve, and a ring piston loosely secured to the base of said mixing chamber constituting means for temporarily checking the movement of the piston valve.

2. A carbureter comprising, in combination, a mixing chamber, ports for admitting air thereto, a piston valve adapted to normally close said ports and to be lifted by suction, and a dash-pot checking means for said piston valve having a self-centering member.

3. A carbureter comprising, in combination, a mixing chamber, ports for admitting air thereto, a piston valve adapted to normally close said ports and to be lifted by

suction, and a dash-pot checking means for said piston valve having a loosely mounted self-centering member.

4. A carburetor comprising in combination a mixing chamber, air ports leading into said mixing chamber, a valve for controlling said ports, a tapered needle valve secured by a ball and socket connection to the air valve, a spray nozzle into which the 10 needle valve projects, and means carried by

the needle valve within the spray nozzle for centering said valve in all positions therein.

Signed at New York city, in the county of New York, and State of New York, this 2nd day of November, A. D. 1914.

ABRAM SCHENCK BERGEN.
